WIRE COIL INSERT

Otto Haas, Richmond Hill, N. Y., assignor to
Aircraft Screw Products Company, Inc., Long
Island City, N. Y., a corporation of New York

Application December 16, 1943, Serial No. 514,438

5 Claims. (Cl. 85—46)

The present invention relates to wire coil inserts for screw connections of the type described, for instance in U. S. Patent No. 2,150,876 of March 14, 1939.

Wire coil inserts of the kind here under consideration require some integral means whereby the coil can be contracted prior to insertion into the tapped hole of a nut or boss member and it is essential for this purpose that a tool inserted in the coil can grip the end advancing into the tapped hole. It is also necessary that after removal of the inserting tool all the coil convolutions are free for engagement by the threading of a stud or bolt member. The well-known inserts are provided with a diametrical tang of its end convolution so arranged that the tang can be broken off after the insertion of the coil is completed. In many instances, however, this is not a desirable design inasmuch as the tang constitutes a waste, as it is difficult to break the tang if the wire has a substantial thickness and as it is difficult in many instances to remove the broken tang when the hole into which the coil is inserted is a blind one.

The present invention contemplates to provide means whereby the mentioned disadvantages can be avoided and essentially consists in that one coil end is provided with a recess on the inner side of the convolution so that a hook-shaped end is produced which does not project from the desired shape of the coil. Further objects and details of the invention will be apparent from the description given hereinafter and the accompanying drawing illustrating embodiments thereof by way of example. In the drawing,

Fig. 1 is a perspective view of a wire coil according to the invention;

Fig. 2 is a front view of a modified portion of the recessed end; and

Fig. 3 is a perspective view of another embodiment.

Referring now to the drawing, Fig. 1 shows a wire coil in general denoted by 1 which has a diamond-shaped cross-section. However, it is to be understood that the invention is applicable to coils of wire cross-section of any form such as round, square or pear-shaped cross-section. The one end convolution 2 of the coil is provided with a recess 3 on its inner side and the flank 4 of the recess close to the ultimate end 5 of the convolution is located in a plane substantially radial with respect to the coil axis 6. It is advantageous in many instances to make the mentioned flank undercut as indicated at 4a in the modification of Fig. 2. The recess should be deep enough so that

5 a tool with a radial projection inserted into the coil may engage the flank 4 safely. On the other hand, sufficient material of the recessed portion should remain to transmit the torque applied by the tool at the flank 4 to the coil convolutions in order to contract the coil for insertion. In most instances, a recess depth of approximately half the wire thickness will be adequate.

10 The end face 5 of convolution 2 may be slanted so that an inner edge 7 is provided which may bite into the material of a bolt screwed into the insert in order to create a locking effect.

15 In many instances it is desirable to gradually decrease the diameter of at least a portion of the end convolution which is leading in inserting the coil in order to facilitate the engagement of the coil with the threading of the member into which it is to be inserted. In this event, the recess is provided in the portion of reduced diameter.

20 This is shown in Fig. 3 where the larger coil body 11 is cylindrical whereas the end convolution 12 is of decreasing diameter so that the end portion thereof projects inwardly with respect to the inner coil cylinder. It will be noticed that according

25 to what has been stated about the coil wire cross-sections Fig. 3 shows a coil of round wire. If an inwardly projecting coil end is provided it is advisable to have it project at least as far as the depth of the recess 13 provided therein. 30 When after the insertion of the coil in a boss member, a bolt or stud is screwed sufficiently deep into it, the bolt or stud portion entering the mentioned end convolution will expand it so as to engage the boss threading the same as the remainder of the coil. The recess 13 with its flank

35 14 otherwise corresponds entirely to the recess 3 and flank 4 or 4a respectively of Fig. 1 or 2.

40 In producing an insert according to the invention I have found that it is advisable to provide the recess after the wire has been wound into coil shape because recessing of the wire prior to the coiling interferes with the uniform shaping of the coil owing to the fact that the stress distribution is not uniform in the recessed and the non-recessed portions of the wire. It will be understood that no particular difficulties are en-

45 countered in providing a recess according to the invention in a coil convolution which projects inwardly as shown in Fig. 3. The providing of 50 a recess in an end convolution of a coil cylindrical throughout as shown in Fig. 1, however, requires a particular method because the tool used in cutting or otherwise making the recess would be apt to interfere with the subsequent convolutions located on the same cylinder as the coil

end. In making a coil according to Fig. 1, I proceed therefore in such a manner that I first wind the wire to form a cylindrical coil, then I bend a portion of one end convolution approximately into the position as shown in Fig. 3 and thereafter apply a tool to recess the end. When the recess is completed, I cause the inwardly projecting end to return to its original position either owing to the natural resiliency of the wire material or by bending it back to the diameter of the main coil body. Whether such restoring of the circular form of the end convolution requires a bending force or whether the resiliency of the material is sufficient for this purpose will, of course, depend on the one hand on the quality of the material and on the other hand on the length of the arc or portion of the end convolution which has been bent inwardly for the application of the recessing tool.

Although I have described my invention in relation to only two different forms, it will be clear to those skilled in the art that alterations and modifications thereof may be made without departing from the spirit and essence of the invention, which shall be limited only by the scope of the appended claims.

I claim:

1. An insert for a screw connection comprising

a substantially cylindrical wire coil, one end convolution of said coil being provided with a recess on its inner side near its free end, said recess having a depth of approximately half the wire thickness and having a substantially radial flank adjacent to said free end so as to form a hook for the engagement of a torque-applying tool.

5. An insert as claimed in claim 1 wherein said flank is undercut.

10. An insert as claimed in claim 1 wherein said free end is tapered from the outside to the inside.

15. An insert for a screw connection comprising a substantially cylindrical wire coil, a portion of one end convolution of said coil having a decreasing diameter so that it projects inwardly with respect to the inner coil cylinder, said projecting portion being provided with a recess on its inner side near its free end, and said recess having a depth of approximately half the wire thickness and having a substantially radial flank adjacent to said free end.

20. An insert as claimed in claim 4 wherein said portion of one end convolution projects inwardly an amount approximately equal to the depth of 25 said recess.

OTTO HAAS.
